UNITED STATES PATENT OFFICE.

WILLIAM M. C. FOSTER, OF CHICAGO, ILLINOIS.

DESIGN FOR A BICYCLE FRONT-FORK CROWN.

45,457.

Specification for Design.

Patented Mar. 24, 1914.

Application filed October 7, 1912. Serial No. 724,485. Term of patent 7 years.

To all whom it may concern:

Be it known that I, WILLIAM M. C. FOSTER, residing at Chicago, in the county of Cook and State of Illinois, have invented a new, original, and ornamental Design for Bicycle Front-Fork Crowns, of which the following is a specification, reference being had to the accompanying drawing, forming part thereof.

The figure is a perspective view of a bicy-

cle front-fork crown, showing my new design.

I claim:

The ornamental design for a bicycle front-fork crown, as shown.

WILLIAM M. C. FOSTER.

In the presence of—

GEORGE A. CHRITTON,
GEORGE S. LEWIS.
